UNITED STATES PATENT OFFICE.

CHARLES G. McCARLLEY, OF JACKSONVILLE, FLORIDA.

RAILWAY-SWITCH MECHANISM.

Application filed June 2, 1922. Serial No. 565,393.

To all whom it may concern:

Be it known that I, CHARLES G. McCARLLEY, a citizen of the United States, residing at Jacksonville, in the county of Duval and 5 State of Florida, have invented certain new and useful Improvements in Railway-Switch Mechanism, of which the following is a specification.

My invention relates to railway switch mechanisms, and particularly to adjustable devices used in connection with power-operated switches for permitting relative motion between the switch operating rod and the head rod connecting the two movable rails 15 of the switch.

I will describe one form of mechanism embodying my invention, and will then point out the novel features thereof in claims.

20 In the accompanying drawings, Fig. 1 is a plan view showing a railway switch having applied thereto one form of adjustable device B embodying my invention. Fig. 2 is a view showing in front elevation the adjustable device B of Fig. 1. Fig. 3 is an end view, partly sectioned, of the adjustable device B shown in Fig. 2. Fig. 4 is a front view of the bracket member 6 forming part of the adjustable device B. Fig. 5 is a bottom view of member 6, the right-hand portion of this view being sectioned on the line V—V of Fig. 4. Fig. 6 is a vertical sectional view of the bracket member 6 taken on the line VI—VI of Fig. 4. Fig. 7 is a 35 view showing in front elevation an adjustable sleeve 13 forming part of the device B. Fig. 8 is a bottom view of the sleeve 13, and Fig. 9 is an end view of the same sleeve.

Similar reference characters refer to similar parts in each of the several views.

Referring first to Fig. 1, the reference character A designates a railway switch comprising as usual two stock rails 4 and 4^a, and two movable rails 2 and 2^a, the movable rails being connected by a head rod 3. The reference character 5 designates an operating rod which is adjustably connected with the head rod 3 by a device B embodying my invention.

50 Referring now to Figs. 2 and 3, the adjustable device B comprises a bracket 6 which is attached to the head rod 3 by means of four bolts 7. As here shown, this bracket is insulated from the head rod by two fibre plates 8 and 9, and also by a fibre bushing 10 surrounding each bolt 7. The fibre plate

8 is located between the bracket 6 and the head rod 3, while the fibre plate 9 is located between the head rod 3 and a wrought iron bracket plate 11 which lies against the opposite side of the head rod from the bracket 6.

The bracket 6 is provided with two ears 6^a, 6^b projecting downwardly from the head rod and disposed in tandem along side the operating rod 5, these ears being spaced apart as clearly shown in Figs. 2 and 4. The surface of each ear confronting the operating rod 5 is recessed at 12, as best shown in Figs. 4, 5 and 6, and the recessed portion is provided with two overhanging lips 12^a, 12^b, the recess and lips together constituting a guide which begins at the outer end of the ear and terminates in a rounded abutment 12^b, as best shown in Fig. 4.

55 Mounted on the operating rod 5 are two adjustable sleeves 13, 13, each of which is constructed as shown in Figs. 7, 8 and 9. Referring to these views, it will be seen that each sleeve is provided with a cored hole 13^a, which is of such size that the sleeve will slide freely on the operating rod 5. The bottom of the sleeve is provided with two flanges 13^b, 13^c, which are so spaced and are of such size as to slide freely in the guide 12 of the ear 6^a. The flanges 13^b begin at one end of the sleeve, and as clearly shown in Fig. 8, they are rounded at the other end to form an abutment 13^c designated to co-operate with the abutment 12^b in each of the 70 ears 6^a.

75 Suitable means are provided for locking each sleeve 13 in adjusted position on the operating rod 5. As shown in Fig. 2 this is accomplished by threading the operating rod at 16, and providing a nut 14 at one end of each sleeve and two similar nuts 15 and 15^a at the other end.

80 As is well understood, the throw of the operating rod 5 is usually considerably greater than the throw of the head rod 3, and the purpose of my invention is to provide a novel and improved means for absorbing the lost motion of the operating rod in such manner that the movements of the 85 head rod will occur during any desired part of the movements of the operating rod. With the parts in the positions in which they are shown in Fig. 2, the operating rod 5 is ready for a right-hand movement, and when this occurs no movement of the head rod 3 will take place until the abutment 13^c on the 90

- left-hand sleeve 13 engages the abutment 12^b on the left-hand ear 6^a. When such engagement takes place, the head rod 3 will be shifted to the right to reverse the movable 5 rails of the switch A. During the free movement of the operating rod 5 the right-hand sleeve 13 will, of course, move away from the abutment 12^b in the right-hand ear 6^a, so that when the left-hand movement 10 of the operating rod 5 takes place no movement of the head rod 3 will occur until the right-hand sleeve 13 returns to such position that its abutment 13^b engages the abutment 12^b in the right-hand ear 6^a.
- 15 To adjust either sleeve 13 on the operating rod 5, it is only necessary to slack off the nuts 15 and 15^a, turn nut 14 forward or back according to the direction of adjustment desired, and again tighten up the two nuts 20 15 and 15^a.

Although I have herein shown and described only one form of mechanism embodying my invention, it is understood that various changes and modifications may be 25 made therein within the scope of the appended claims without departing from the spirit and scope of my invention.

Having thus described my invention, what I claim is:

- 30 1. In railway switch mechanism comprising switch rails, a head rod connecting said rails and an operating rod for moving the switch, the combination with the foregoing instrumentalities of a bracket attached to the head rod and provided with two spaced ears disposed in tandem relation alongside the operating rod, a guide on each ear formed by a recess and two overhanging lips, said guide beginning at the outer end 35 of the ear and terminating in an abutment near the inner end, two sleeves adjustably mounted on said operating rod, one for each ear, and each having flanges co-operating with said guide in the ear and an abutment 40 co-operating with the abutment in the ear, and means for locking said sleeves in adjusted positions on said operating rod.
- 45 2. In railway switch mechanism comprising switch rails, a head rod connecting said rails and an operating rod for moving the switch, the combination with the foregoing instrumentalities of a bracket attached to said head rod and provided with two spaced ears located in tandem relation alongside 50 said operating rod and each having an abutment, two sleeves adjustably mounted on said operating rod, one for each ear, and each provided with an abutment co-operating 55 with the abutment on the associated ear, and means for locking said sleeves in adjusted 60 positions on said operating rod.

3. In railway switch mechanism comprising switch rails, a head rod connecting said rails and an operating rod for moving the switch, the combination with the foregoing 65 instrumentalities of a bracket attached to said head rod and provided with two spaced ears located in tandem alongside the operating rod, two sleeves one for each ear and each 70 adjustably mounted on said operating rod, means for limiting the movement of each sleeve with relation to the associated ear, and means for locking each sleeve in adjusted position on the operating rod.

4. In railway switch mechanism comprising switch rails, a head rod connecting said rails and an operating rod for moving the switch, the combination with the foregoing instrumentalities of a bracket attached to said head rod and provided with two spaced ears located in tandem alongside the operating rod, two sleeves one for each ear and each 75 adjustably mounted on said operating rod, means for limiting the movement of each sleeve with relation to the associated ear, screw threads on said operating rod, and 80 nuts coacting with said threads to lock said sleeves in adjusted positions on the operating rod.

5. In railway switch mechanism comprising switch rails, a head rod connecting said rails and an operating rod for moving the switch, the combination with the foregoing instrumentalities of a bracket attached to said head rod and provided with two spaced 85 ears located in tandem alongside the operating rod, two sleeves one for each ear and each 90 adjustably mounted on said operating rod, means for limiting the movement of each sleeve with relation to the associated ear, means for constraining said sleeves to move in a fixed path with relation to said bracket, and means for locking said sleeves in 95 adjusted positions on said operating rod.

6. In railway switch mechanism comprising switch rails, a head rod connecting said rails and an operating rod for moving the switch, the combination with the foregoing instrumentalities of a bracket attached to one of said rods and provided with two spaced ears located in tandem relation alongside the other rod, an abutment on each ear, two sleeves adjustably mounted on the said other rod and co-operating 100 with said two abutments respectively, and means for locking said sleeves in adjusted 105 positions on the rod on which they are mounted.

In testimony whereof I affix my signature.

CHARLES G. McCaulley.
